CAN OPENER

Denis Farandatos, New York, N. Y.

Application November 21, 1950, Serial No. 196,809

6 Claims. (Cl. 30—8.5)

1

This invention relates to a can opener. The problems relating to can openers arise not only in the home but particularly in restaurants, where hundreds of cans containing different foods may be opened in sequence by a single opener. Such an operation involves questions of cleanliness and contamination. Contamination occurs when an opener which has just been used to open a can of one kind of food, for instance beans, is subsequently used without cleansing to open another kind, for instance berries. Some residue from the first can is transferred to the second by the knife. This problem of contamination has a graver side because the knives of can openers, in cutting the metal of the can, sever tiny particles of metal which fall into the contents of the can, and this contamination increases as the knife grows older and duller. Such particles of metal are injurious, and have been recognized as such by dietary authorities. The degree of such contamination by metal particles is of sufficient magnitude to constitute a real problem.

The question of cleanliness is much in evidence in restaurant practice, as can tops are not clean, and as the severed tops of cans fall into the contents of the can and slowly submerge. The usual method of extracting the top is to push one side of the top downward with a finger so as to raise the opposite side above the food level, grasping the raised edge of the can before it submerges. The fingers of the operator thus enter the food of successive cans.

There is, in good restaurants, a rule that the opener shall be cleaned between uses, or between different uses, but cleaning of prior openers is time consuming, and in the absence of a reminder the rule is honored in the breach rather than the observance. The openers must usually be washed as a whole, which cannot be done well except by mechanical washers.

It is an object of this invention to make a can opener which will prevent the contamination of the food in cans by severed particles of metal, which will prevent severed can tops from falling into the food, which will make it unnecessary for the operator to fish for the can top in the food with his fingers, and which will physically remind the operator to wash the knife.

Many can openers are so constructed that the entire opener must be washed in order to wash the blade.

It is an object of this invention to make a can opener having a removable blade which can be removed from the remainder of the mechanism for independent cleaning.

Another object of the invention is to present an electromagnetic can opener that cannot be operated until the current is turned on, which has a magnetized and removable blade, and an electrical-mechanical interlock.

The objects of the invention are accomplished, generally speaking, by the conceptions herein described, a preferred reduction to practice of which is illustrated in the drawing, wherein:

10 Fig. 1 is a vertical sectional view through such a can opener in the process of opening a can;

Fig. 2 is an elevational view of the opener taken from the left side of Fig. 1;

15 Fig. 3 is a plan view of the can opener with the raised handle in section;

Fig. 4 is a section on the line 4—4 of Fig. 1;

Fig. 5 is a section on the line 5—5 of Fig. 1 with the head locked to the base;

20 Fig. 6 is a section on the line 6—6 of Fig. 3; and,

Fig. 7 is a perspective view of the main head casting.

Referring now to the numerals of the drawing, 10 is a table top, or the like, to which is affixed as by screws 11 a base plate 12 which is of hollow construction and raised above the table by side and end flanges 13. A plate 14 extends between the side flanges at the table level at the front of the opener (Figs. 1 and 5). Projecting downwardly from the plate 14 are cylindrical bosses 15; extending upwardly from plate 12, in line with bosses 15 are cylindrical bosses 16. The aligned bosses 15, 16 constitute bearings for vertically movable standards 17 which support the upper part or head of the can opener.

25 35 Heretofore, some difficulty has been experienced in securing proper alignment of the knife and the can edge, and in securing the true rotation of a can during cutting. Particular difficulty has arisen in handling cans of different size, some of which may be very large and heavy and must be supported on an adequate base.

This invention includes a new conception for solving this problem. According to the invention, there are mounted beneath the top of the base 12 axles 18, which are received between lugs 19, 20 and held in position by wedges 21, screw mounted in lug 20, the offset ends of such wedges forcing the ends of the axles 18 firmly into their seats between the lugs by lever action (Fig. 6). Mounted on these axles 18 are rollers 22 which extend upward through slots 23 in the base plate 12 so that any can which rests upon the rollers is supported out of contact with the base plate. The rollers are radially arranged with respect to 55 a wheel 24 which is mounted upon an axle 25

seated in an apertured boss 26 extending downward from the base plate 12. The wheel 24 is provided with a cylindrical ledge 27 which supports the edge of the can beneath the cutting blade of the can opener, and with an upstanding flange 28 which correctly positions the can for the action of the knife. When thus supported upon the wheel and the radial rollers, cans of any size can be opened with the utmost efficiency, rotating readily upon the rollers and wheel.

Means are provided for locking the head to the base and a part of that mechanism is mounted in the base. A latch 29 of reclining L-shape is supported upon the bottom plate 14 by a roller 30 which is mounted on the latch. The latch is drawn into locking position by a spring 31 which is attached to a boss 32 depending from the base plate 12. Slotted bell crank lever 32' is pivotally mounted upon a lug 33 attached to a strap 34 which is mounted at its ends on the plate 12. A lug 35 depends from a plate armature 36 which is received in a recess at the forward end of plate 12 and which can be drawn upwardly by the attraction of an electromagnet located in the head. When this plate armature is thus attracted it is moved upwardly, pivoting the bell crank lever 32' around its pivot on lug 33, overcoming the force of spring 31 and moving the latch 29 out of locking position. It will be apparent from this description that when the head is locked to the base by latch 29, the head cannot be lifted into operating position until the electromagnet has been energized. This prevents the operator from using the can opener without energizing the magnetic portions of the can opener.

The head and cutting parts of the opener are supported on the upper ends of standards 17.

The head comprises a metal cover and support 40 rigidly carried on the upper ends of standards 17, which are received in hollow bosses 41 which project downwardly from the cover 40. The upper ends of the standards are screw threaded into the bosses and held in set position by nuts 42. Supported by the head are bearings 43, 44 and the main casting 45, which constitute the backbone of the head, and support the main shaft 46 in a position fixed vertically with respect to the head. A knurled collar 47 is fixed to the lower end of rotatable shaft 46 by a pin 47' to grip the edge of the can and rotate it against the edge of the knife.

The upper end of this shaft carries a head 48 to which is pivoted a handle 49 having a fork 50 which embraces the head and is provided with cam surfaces 51 (Fig. 1) which engage a sleeve 52 which is vertically slidable along shaft 46 to engage a washer 53 which is in engagement with the upper surface of the ends of a fork 54, the lower surfaces of which engage a washer 55 which is under the thrust of a spring 56 which bears upon the bearing 43. When the handle is in the raised position of Fig. 1, the sleeve 52 is depressed by cam 51 and spring 56 is compressed. The downward motion of sleeve 52 acts upon the yoke 54 and tilts the entire blade mechanism about a horizontal pivot 57 which is mounted at its ends in the main casting. The main casting has lugs 58, 58' which depend and carry the shaft 57. Mounted upon this shaft is a casting 60 which is provided with upstanding perforating lugs 61, 62 the perforations of which receive the forked bolt 63 which is thrust by spring 64 toward the right of Fig. 1 and through apertures 65 in the upper part of knife 66 and corresponding apertures in the guide 70. Bolt 63 is provided with an up-

standing finger grip 67 which permits it to be drawn back, releasing the knife, which can be withdrawn by means of a finger grip 68. The casting 60 extends downward alongside the knife and a U-shaped guide 70 is attached by screws 71 to the sides of the downwardly extending part, the guide being spaced from the face of the casting just enough to receive the knife blade. The arms or yoke 54 constitute a part of the casting 60 so that it will be apparent that when the handle 49 is raised to the position of Fig. 1, depressing sleeve 52, the casting 60, and all the parts carried by it, are pivoted around shaft 57 in such a direction that the knife 66 moves away from the knurled collar 47, thus providing adequate room for the reception of the rim of a can.

A can having been placed upon the base as shown in Fig. 1, the head is struck downward, the handle 49 being still in the raised position, and the point of knife 66 pierces the top 72 of the can adjacent the wall. The lever 49 is now lowered to the position shown in Figs. 2 and 5 and the spring 56 exerts upward pressure against arms 54 of casting 60 tending to pivot the frame 60 about shaft 57 and forcing the blade 66 toward the wall of the can as the collar 47 is rotated by shaft 46 and handle 49, thus producing a cut adjacent the very wall of the container and tending to smooth the severed material against the wall.

Small particles of metal adulterate the contents of the can, when prior art openers are used, but means have been provided to overcome that objection, because the blade of the knife is magnetized.

A cord 80 is provided with a plug for attachment to the usual outlet of an electric light circuit, connecting at 81 with a switch 82 having an on-off lever 83, and through the switch at 84 and connection 85 to one side 86 of a solenoid 87. The current leaves the solenoid through line 88 which is part of the cord. A brass plate 89 is attached to casting 60 and supports one end of solenoid 87, the other end of which is supported by the depending leg of casting 60. One pole 90 of the solenoid is extended by means of a plate 91 of magnetizable metal, the end of which is in a plane with the lower end of casting 60. A copper band 92 is placed around the end of pole 91, constituting it a shaded pole. The lower end of casting 60 is quartered and one quarter 93 is wrapped in a copper band 94 thus constituting it a shaded pole.

These poles engage, or approach the top of the can in the cutting position of the knife so that the lifting of the head removes the top of the can after severing is complete. The steel knife, which is of magnetizable metal, is engaged with the vertical leg of casting 60 which in turn supports the pole 95. Thus, the knife is itself magnetized and it catches and retains the small particles of metal which are separated by the knife and would otherwise fall into the food.

A magnetic bridge 96, which is pivotally attached to the lower end of casting 60, drops into place upon the end of pole 91 and serves to prevent flux losses when the opener is not in use. A depending bumper 97 raises the magnetic bridge out of the way when the next can is opened.

The head carries a horizontally arranged, spring pressed bolt 98 having a cam face adapted to engage the cam face 29' of latch 29, retracting the bolt and allowing the locking faces of latch and bolt to engage. At the same time, a vertically slidable locking lever 100 enters the opening 101 in base 12 and passes behind latch 29 so that

it cannot be disengaged without lifting the lock. The lock 100 is vertically, slidably mounted in a slotted extension 102 of the main casting of the head. This lock is released when the bolt 63 is drawn out to permit the cleansing of the knife 66, by the following mechanism.

Mounted on the end of the shaft 57 is a lever 103 the end of which engages beneath the bent end of lock 100 as shown in Fig. 1. A shorter arm 104 extends upward and carries a pin 105 which projects inward and enters a notch 106 in the underside of the shank of forked bolt 63. It will be observed in Fig. 4 that the bolt 63 which holds the knife in position has a forked end which supports both sides of the knife, and a shank to which the finger grip 67 is attached. When the finger grip is pulled out, to release the knife, the long end of the lever 103 lifts up the lock 100, which enables the latch 29 to be released, but this release will not occur unless the electromagnetic circuit is in operation. There may be a loose fit between the latch 29 and its cooperating bolt so that the upward motion of the head will release the latch 29 by moving the plate armature 36, which is attracted by the poles 91, 93 just as the can top is attracted in a different position of the head, or the spacing of poles and armature, in lowered position of the head, may accomplish the same result.

The can opener operates as follows: The operator finds the head locked to the base, and in order to free it, turns on the switch 83, energizing the solenoid 87, but discovers that he still cannot free the head from the base. He, therefore, recalls that he must release the knife 68 and wash it. He releases the knife by finger grip 67, removes it, inspects it for cleanliness, cleans it if need be, and returns it to its guide. Then he pulls the finger grip 67 which operates the lever 103, releases the lock and enables him to raise the head. In raising the head, the poles of the electromagnet lift the plate armature 36, which operates through crank 32 to move the latch 29 to unlocking position. In that position the lock 100 is prevented from passing downward behind the latch 29. In raising the head the handle automatically lifts to vertical position, depressing the sleeve 52 and tilting the mechanism within the head around pivot 57, providing ample room between knurled collar 47 and the blade of the knife for the reception of a can rim. A can is placed on the radial rollers 22 and the positioning wheel 24, abutting the flange 28, and the knife is driven through the can cover by a sharp downward motion of the head. The handle is brought to horizontal position and cutting of the can top begins by turning the handle. Firm pressure is maintained on the rim between the blade and the knurled collar by the pressure of spring 56, which tilts the mechanism toward gripping position about shaft 57. When the cutting is finished the head is lifted, taking with it the can cover, the can is set aside, the cover is thrown away, the head is returned to locking position, the knife is removed and cleaned and the process is repeated.

The can opener can be used to open a plurality of cans by holding the head in elevated position, and it is desirable that this should be possible, as it does no harm to open several cans of one kind of food without cleaning the knife, as the minute particles gather on the blade until they are manually removed therefrom. However, the head is always returned to the base after the opening of a few cans, for one reason or another,

and the operator takes the opportunity to clean the knife.

The entire head is so constructed that it can be washed in the usual spray washing mechanism. The solenoid is encased in heat hardening plastic of water-proof characteristics and similar treatment is extended to the wiring.

Among the major advantages of the invention are the magnetizing of the knife, the extraction of the severed can top and the exclusion of fingers from the food. The magnetizing of the knife prevents the contamination of food with the small metal parts torn from the metal of the can. The can cover, being part of the outside of the can, is seldom clean, usually dirty from accumulated dust and handling, and the attraction of that cover by the solenoid poles prevents that exterior dirt from getting into the food. The food is uncontaminated by fingers, because no reason exists to compel the operator to thrust his fingers into the food to recover the can top.

Frequent injuries result in ordinary restaurant practice because the hands of operators are cut by the sharp metal of the severed can or top. Such injuries are prevented by this apparatus because there is less occasion for the operator to put his hands near the severed edges.

An improvement in cleanliness is also obtained because the knife is made independently removable and can be cleaned as frequently as desired. Heretofore, it was frequently impossible to clean the knife except as a part of the whole can opener, which could only be done satisfactorily by a spray washer which put the opener out of service for so long a period of time that the operator would not ordinarily clean it during the course of the working day.

The electrical mechanism is encased and sealed in waterproof plastic so that the entire head can be washed.

Other advantages of the invention will be apparent to those who are engaged in the preparation of canned foods.

The invention is particularly useful to government agencies, some of which open cans in enormous quantity.

As many apparently widely different embodiments of the present invention may be made without departing from the spirit and scope thereon, it is to be understood that the invention is not limited to the specific embodiments.

What is claimed is:

1. A can opener having a head, guide means supported by said head, a knife slidably in said guide means, and means to lock the knife in the guide means comprising a spring pressed plunger.

2. A can opener comprising a thrusting blade, guide means supporting said blade, a spring pressed bolt passing through blade and guide means and means to retract the bolt to free the blade for removal from the guide.

3. A can opener comprising a blade guide, a blade slidably received in said guide and having exposed gripping means, and bolt means penetrating said guide and blade and having exposed gripping means for withdrawing the bolt to release the blade.

4. A can opener comprising a base including a can support, a standard associated with said base, a cutting head associated with said standard movable toward and away from the base, and locking means having parts associated with the base and cooperating parts associated with the head functioning to lock the base to the head

when head and base are brought into proximity, said lock means having a manually operable release means.

5. A can opener having a frame, can cutting means associative with said frame, support means associated with said frame adapted to receive said can cutting means, and lock means associated with the support means and the cutting means to hold the cutting means in operative position in association with the frame.

6. A can opener having a frame, can cutting means associative with said frame, support means associated with said frame adapted to receive said can cutting means, and lock means associated with the support means and the cutting 15 means to hold the cutting means in operative position in association with the frame, said lock

means comprising a manually operable release for said cutting means.
